RAZOR OF THE VIBRATORY TYPE

George R. Bott, Stamford, Conn., The Stamford Trust Company, executor of said George R. Bott, deceased.

Application April 17, 1937, Serial No. 137,519

1 Claim. (Cl. 30—43)

This invention relates to razors, and more particularly to that type in which either a rotary or reciprocatory cutter is applied directly to the skin, and acts in conjunction with a second cutter.

This invention has for its object to provide a cutter head having an adaptor which embodies certain improved features in the type of razor referred to, and which may be substituted for 10 razor heads heretofore used, so that the motor mechanism in a handle casing of other types of razors may be utilized. Or, the improved head with its adaptor may be merely applied to a mechanism to obtain the necessary oscillation.

15 The invention also has for its object to provide a smooth-running and close-cutting razor, and finally, one of parts which are simple in manufacture under mass production.

More particularly, the invention consists of a 20 detachable head having an adaptor, which may be readily connected to means for moving it.

To carry out these objects, the invention embodies novel means hereinafter more fully described, with embodiments thereof shown in the 25 drawings, and finally pointed out in the claim.

In the accompanying drawings:

Figure 1 is a vertical transverse section taken on line 1—1 of Figure 3;

Figure 2 is a vertical transverse section taken on line 2—2 of Figure 3;

Figure 3 is a plan view of Figure 1;

Figure 4 is a side view broken away to show a section taken on the longitudinal cross section line 4—4 of Figure 3;

Figure 5 is an end view of Figure 3;

Figure 6 is a perspective view of the spring and its tongues; and

Figure 7 is an end view of another form of 50 razor consisting of the head shown in Figures 1 to 5 combined with the handle of the conventional safety razor, and also provided with means to reciprocate the movable cutter.

Similar characters of reference indicate corresponding parts throughout the various views.

Referring to the drawings, and more particularly to Figure 1, the razor head 10 consists of a cap 11, movable skin contacting cutter 12, and stationary comb-cutter 13, all supported by an umbrella stem portion 14 having a shank 15. Exterior to the shank 15 at a point near the bottom of the head, is a triangular recess 16 adapted to be engaged by a holding screw 18 which passes through a casing or other support shown in dotted lines by 17. The head 10 is detachable, it being only necessary to turn the screw 18 or

other fastening device and remove the head 10 from its support. It may be replaced by inserting the head 10 in a recess 19 of the support 17, when, by fastening the screw 18, the head is ready for operation, the adaptor arm 32 being 5 ready to engage a mechanism for moving it.

This detachability and replacement is important, in that the improved head with its adaptor can be applied to casings of other razors where-in the motor or vibrating mechanism is satisfactory but where the cutting action is not. Also, the cutter mechanism may be more readily cleaned, without danger of having the cleaning water rust the mechanism of the motor. The head 10 may be applied to any suitable handle 15 in which a vibratory member 20 moves, which member 20 serves to oscillate, vibrate or reciprocate the movable skin contacting cutter member 12 longitudinally of the structure shown in plan view in Figure 3. An embodiment closely resembling the handle of the ordinary conventional non-vibrating safety razor, is shown in Figure 7, in which the handle 60 has a hollow portion 61, and a bayonet slot connection 62 adapted to be engaged by a pin 63 of the head 64, which has a round or cylindrical base portion 65 adapted to fit into the hollow portion of the conventional handle 60. This head 64 has an adaptor 66, which by suitable mechanism not shown is operated by means of a flexible coil 67 having a rotary or reciprocating wire 68 therein.

Interposed between the cap 11 and the movable skin contacting member 12, is a spring 22, formed of a plate having a body portion 23, and three tongues 24 on each side thereof, as shown 35 in Figure 6. The body portion 23 rests against and is seated in the under or interior side of the cap 11, as shown in Figs. 1, 2 and 4. The body portion 23 is provided with two holes 25 through which circular lugs 26 of the caps pass, 40 and by a reasonably close fit of lug and hole, the spring is held in position without vibrating. The tongues 24 are bent downwardly as shown in Figure 6, and exert a gentle pressure against the cutter 12 and in turn cause the cutter 12 to press 45 against the stationary cutter 13, so that the cutting edges of the cutters 12 and 13 are brought closely together during cutting action. This pressure of the spring tongues 24 also keeps the cutter 12 in automatic adjustment. The other 50 side of the cutter 12 rests against lubricating means 29, consisting of a recess 27 in the head 10, a registering opening 28 in the cutter 13, and a wick-like insert 29 saturated with a suitable lubricant. The insert 29 extends from the re- 55

cess 27 to the surface of the cutter 12. The lubricant in small quantity passes between the cutters 12 and 13, and thereby facilitates the movement of cutter 12 over the cutter 13.

5 The movable cutter 12 has a centrally disposed opening 30 which is engaged by the end 31 of an arm 32 adapted to be vibrated, the end 31 engaging with a reasonably close fit the opening 30. The lower end of the adaptor arm 32 has a 10 sleeve-like member 34 into which the arm 20 of a well-known motor mechanism may be readily inserted. Thereby, connection between the vibratory arm of a known motor mechanism or other means for vibration, is established. The base 35 in the head allows for the necessary clearance of 15 vibrating members.

To hold the cap 11 and stationary cutter 13 to the head portion 14, the cap 11 is provided with a recess 37 into which the head 38 of a bolt 39 20 fits. The bolt 39 has a shoulder or collar 40 which rests upon the stationary member 13, and which passes through an elongated opening 41 of the movable cutter 12. The bolt 39 then passes 25 through a hole 42 of the head portion 14, and has a threaded end 43 enter a recess 45 of the shank 15, in which recess a screw nut 46, having a knurled shoulder 47, is inserted. Preferably, there are two such bolts 39 and correlated parts, as shown in Figures 3 and 4, to act as a 30 balancing pair. The removal of the bolts and disassembly of the parts permits of inspection and cleaning.

The top plate 11 extends from one end of the 35 razor to the other, as shown in Figure 3, and at each end is provided with shoulder guard portions 50 extending from the top of the rounded or dome-shaped plate downwardly to the sides of the razor, as shown in Figures 3 and 5. These exterior guards confine the shaving operation 40 between the same. The ends of the plate 11 have also downwardly extending flanges 51, entering recesses 52 of the member 14, so arranged to al-

low play therewithin of the reciprocating cutter 12. The teeth 53 of the cutter 12 and the teeth 54 of the comb cutter 13, extend between the shoulders 50.

The size of the teeth may be different on one 5 side than on the other, to accommodate different hair cutting conditions. On the right hand of Figure 3 the teeth are finer than those on the left hand side of the razor there shown.

It will have been noticed that the detachable 10 head has an adaptor, which, when the head has been attached to any suitable handle or motor casing having means for operating the adaptor, the movable cutter is actuated. This enables the improved head with the adaptor to be attached to 15 a motor casing of another type of vibratory razor whose cutting has been found to be unsatisfactory. Also, the improved head may be actuated by a flexible cable having a wire, as shown in Figure 7.

While I have illustrated and described the preferred form of construction for carrying my invention into effect, this is capable of variation and modification without departing from the spirit of the invention. I, therefore, do not wish 25 to be limited to the precise details of construction set forth, but desire to avail myself of such variations, modifications and adaptations as come within the scope of the appended claim.

I claim:

In a razor of the vibratory type, the combination of a support having a recess, a cutter on said support having teeth, and having an opening, a second cutter having teeth movable in respect to the first cutter, and lubricating means in said recess, said recess acting as a reservoir, and said lubricating means extending from said recess through the opening of said cutter, and acting against said second cutter near the teeth thereof.

GEORGE R. BOTT.
